JEWELRY CLIP

Jack Ruderman, New York, N.Y.

Application March 24, 1945, Serial No. 584,702

16 Claims. (Cl. 63—20)

1

It is among the objects of the invention to incorporate in any of the variety of articles of costume jewelry, means for retaining a modicum of perfume, in lieu of applying the perfume directly to the body or to the garment.

Among the more specific objects of the invention are to provide the sheet metal clip, commonly a hinged clip of costume jewelry such as dress clips, earrings and the like, with a holder for securely retaining a perfume-impregnated piece, such as a porous wad, wick or rod, which holder is integral and unitary with and capable of being formed in a one-step die operation with the clip, and admits of ready introduction and removal of the wad, wick or rod.

Another object is to provide a clip, incorporating a unitary integral holder capable of retaining a perfume-impregnated wad, wick or rod, which clip may be stamped with said socket by means of a single die in any of a wide variety of shapes and sizes for more or less universal adaptation to a variety of articles of jewelry, of which it is to be a part.

In the accompanying drawings, in which are shown one or more of various possible embodiments of the several features of the invention,

Fig. 1 is a plan view of a jewelry clip.

Fig. 2 is a perspective view on a slightly smaller scale, showing said jewelry clip assembled with an illustrative article of jewelry with which it is to be used,

Fig. 3 is a view in transverse cross-section taken on line 3—3 of Fig. 2,

Fig. 4 is a detailed view in longitudinal cross-section taken on line 4—4 of Fig. 2, and

Figs. 5, 6, 7, 8 and 9 are views similar to Fig. 1, showing various forms of clip capable of being stamped from sheet metal with the use of the same die from which is stamped the clip of Fig. 1.

Referring now to the drawings, the clip member or plate 10 of Figs. 1 to 4 may be of a sheet metal blank and in its general outer contour be of conventional form. It includes a hinging end 11 by which it is spring-hinged in conventional manner to the face 12 of the article of jewelry, such as a dress clip, an earring or the like.

According to the present invention, there is formed as a unitary part of the clip plate and extending to the front face thereof, a holder, preferably in the form of a socket for removably holding or retaining a porous wad or wick 13 of cotton, glass fiber or felt or a rod of porous plastic, clay or of the other porous material, impregnated with perfume.

In the specific embodiment shown, the holder

2

is stamped as a unitary part of the clip plate and is preferably near the hinge end 11 thereof and desirably the holder is a socket S extending longitudinally of the clip. To this end, the clip 10 has struck out therefrom a pair of symmetrically arranged tongues 14 and 15, the roots of which are nearest the axis of the clip and face each other as shown, leaving an intervening bridge 16 longitudinally of the clip, the said tongues being preferably rectangular in shape and of length considerably greater than their widths. The tongues 14 and 15 are bent outward about their roots 17 at the lateral edges of bridge 16 and are curved over throughout their width, as shown, with their edges 18 and 19, respectively, parallel but spaced slightly as at 20. The tongues 14 and 15, with the intervening bridge 16, determine desirably a semi-circular cylindrical socket, as shown.

20 Preferably, a semi-circular tongue 21 stamped from the blank of the clip beyond the lower or inner lateral edges of the tongues 14 and 15 is bent forward as shown, at right angles to the plane of the clip to form the bottom of the socket.

25 Desirably, though not necessarily, the metal of the tongues 14 and 15 has small perforations 22 therein to assist in escape of the perfume vapor. The socket S, it will be readily seen, stiffens the clip 10 near its root and therefore adds to, rather than detracts, from the utility of the clip in the performance of its clamping or clasping function.

30 As will readily be understood, a wad or cotton or of felt or a porous rod of appropriate shape, may be introduced into the socket through the open end thereof. This may be conveniently effected, as suggested in Fig. 4, by a resort to a pin 23 pressed against the wad while passed along the slot 20 in the socket, to push the wad inward until it abuts against the bottom tongue 21.

35 A drop or more of perfume may be applied to the wad, wick or rod before, or preferably after introduction of said porous piece into the socket.

40 The socket S, in no wise interferes with the effective closure or clamping action since it fits in the space between the face and the clip plate even when the latter is closed. The socket S is completely concealed by the face of the article of jewelry. Moreover, the wad, wick or porous rod is securely retained and not apt to become lost. Obviously, the wad, wick or rod can be readily withdrawn, as desired, by resort to a pin in the same manner, shown in Fig. 4, in which it was introduced.

45 50 55 While the socket may be incorporated in any

of a wide variety of different jewelry clip plates, there is shown in the drawings one particularly desirable application thereof, adapted for universal use of the same socket as part of any of a wide variety of clip plates, all stamped with the carrying socket above described in a single operation, by use of one and the same die.

To this end the clip plate 10, as shown in Fig. 1, has an elongated body 25 and lateral wings 26 unitary therewith. Near the root of the body, and between the wing 26, is formed the socket S previously described. The length of the body is desirably of open work construction for lightness and for the convenience pointed out below. To this end, the body may be symmetrically cut out to afford a peripheral frame 27, a central longitudinal rib 28, and connecting cross ribs 29 extending outward from the latter to the peripheral frame 27. The slots 30 left by the socket-forming tongues 14 and 15 are preferably aligned at their outer edges 31 with the inner edge 27' of the frame 27 for attractiveness of design.

The wings 26 are preferably also open work as shown, the roots of said wings being cut away as at 32, preferably to form an edge 33 in alignment with the outer periphery of the frame 27, thereby to enhance the ornamental appearance of the clip and to leave a short bridge 34 connecting the outer end of the wing 26 to the body 10 and a short bridge 35 aligned with the innermost cross rib 29', to connect the inner end of the wing to the body.

The clip 10 shown in Fig. 1 is, of course, for a large article of jewelry. As clear to those skilled in the die maker's art, the die can be so set as to shorten the body, as best shown in Fig. 5, by terminating the clip at the outer cross-ribs 29, or, as shown in Fig. 6, at the inner cross-ribs 29'. Obviously, in each of the three embodiments set forth, i. e., with the body full length as in Fig. 1, of intermediate length as in Fig. 5, or of short length as in Fig. 6, the wing structures 26 may be omitted, as shown respectively in Figs. 7, 8 and 9, in each case forming a clip suitable for a particular size of jewelry.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. In an article of jewelry of the type having a sheet metal clip blank; the combination therewith of a holder integral with said clip, said holder including curved elements stamped from the metal of the clip blank, protruding from the plane of the clip and determining retaining means for holding a perfume-impregnated piece against the body of the clip.

2. In an article of jewelry of the type having a sheet metal holding clip blank; the combination therewith of a generally integral holder, said holder comprising a plurality of tongues struck from the body of the clip blank and curved into substantial edge-to-edge juxtaposition and forming a socket in cooperation with the body of the blank.

3. In an article of jewelry of the type having a sheet metal holding clip blank; the combination of an axial socket, said socket comprising

tongue elements stamped from the blank and presenting an elongated longitudinal slot between adjacent tongue ends, for convenience of introduction and removal of a perfume-impregnated piece.

4. In an article of jewelry of the type having a sheet metal clip blank; the combination therewith of a pair of opposed tongues struck out from the blank of said clip, of width greater than their length and with a longitudinal bridge therebetween, said tongues being curved outward and rearward with their outer edges in contiguity with each other, thereby forming a socket in cooperation with said bridge.

5. In an article of jewelry of the type having a sheet metal clip member; the combination in which the clip has a pair of symmetrically arranged opposed struck-out tongues of uniform width with outwardly directed free ends, said tongues having an intervening longitudinal bridge, said tongues being curved forward from the plane of the clip with their outer edges in contiguity to form in cooperation with said bridge a substantially semi-cylindrical wad holder.

6. In an article of jewelry of the type having a sheet metal clip blank; the combination in which the blank has a pair of symmetrically arranged opposed struck-out tongues of uniform width having an intervening longitudinal bridge, said tongues having inwardly directed free ends, said tongues being curved forward from the plane of the clip with their outer edges in contiguity, and a generally semi-circular tongue struck out from the blank beyond the end of the curved tongues and bent inward and forward to constitute the bottom of a generally semi-cylindrical holder formed by the bridge in cooperation with the curved lateral tongues.

7. In an article of jewelry of the type having a sheet metal clip blank; the combination in which the clip has a pair of symmetrically arranged opposed struck-out tongues of uniform width having an intervening longitudinal bridge, said tongues having inwardly directed free ends, said tongues being curved forward from the plane of the blank with their outer edges in contiguity and a generally semi-circular tongue struck out from the blank beyond the inner ends of the curved tongues and bent inward and forward to constitute the bottom of a generally semi-cylindrical holder formed by the bridge in cooperation with the curved lateral tongues, the edges of the lateral tongues being spaced to afford a guide-way for a pin in introducing and removing a wad with respect to the socket.

8. A die-cut sheet metal jewelry clip, having a body and lateral wings, said clip having ornamental cut-outs therein, and having symmetrically arranged cut-out tongues curved forwardly and determining in correlation a socket for retaining a perfume-impregnated wad.

9. A jewelry clip blank, comprising a body and a pair of lateral wings unitary therewith, the body having symmetrically arranged sets of cut-outs, determining an outer relatively narrow frame, a longitudinal axial rib and connecting cross-ribs between the axial rib and the outer frame, the wings being cut out and having a pair of bridges connected with the body, whereby a single die may be set for stamping out any of a plurality of different shapes and sizes of clips with or without wings and with the body terminating at any of the cross ribs.

10. A jewelry clip blank, comprising a body and a pair of lateral wings unitary therewith, the

body having symmetrically arranged sets of cut-outs determining an outer relatively narrow frame, a longitudinal axial rib and connecting cross-ribs between the axial rib and the outer frame, the wings being cut out and having a pair of bridges connected to the body, the body having stamped out tongues between said wings, curved forward therefrom and determining a perfume-wad-retaining socket, whereby a single die may be set for stamping out any of a plurality of different shapes and sizes of clips, each with a socket symmetrically of its body, and with or without wings and with body terminating at any of the cross ribs.

11. In an article of jewelry of the type having a sheet metal clip blank; the combination in which the clip has a number of struck out tongues formed as a wad or wick holder and having juxtaposed edges spaced as a track for a pin to be used in introduction and removal of the wad or wick. 15 20

12. In an article of jewelry, a metal finding element consisting of a flat sheet metal hinge stamping and a plurality of tongues stamped upwardly therefrom and turned inwardly substantially above said stamping, said tongues in combination forming a tubular receptacle.

13. In an article of jewelry, a hinged clip finding back comprising a plurality of tongues extending substantially upwardly and then turned inwardly and forming a box-like receptacle on the inside face of said back, said tongues forming three sides of a receptacle, and the other side being open to permit insertion of a perfume carrying element.

14. In an article of jewelry, a hinged clip finding back comprising a plurality of tongues extending substantially upwardly and then turned inwardly and forming a box-like receptacle on the inside face of said back, two of said tongues

forming the opposite sides of said receptacle and being turned inwardly to form the top of said receptacle, the finding back itself forming the bottom of said receptacle.

5   15. In an article of jewelry, a hinged clip finding back comprising a plurality of tongues extending substantially upwardly and then turned inwardly and forming a box-like receptacle on the inside face of said back, two of said tongues
10 forming the opposite sides of said receptacle and being turned inwardly to form the top of said receptacle, the finding back itself forming the bottom of said receptacle, said receptacle having a plurality of perforations in the walls thereof.

16. In an article of jewelry, a hinged clip finding back comprising a plurality of tongues extending substantially upwardly and then turned inwardly and forming a box-like receptacle on the inside face of said back, said tongues forming three sides of a receptacle, and the other side being open to permit insertion of a perfume carrying element, and the top of said receptacle being slotted to enable said perfume carrying element to be moved into the receptacle.
